UNITED STATES PATENT OFFICE.

JOHN HENRY BECKER, OF RICHMOND HILL, NEW YORK, ASSIGNOR TO WARP TWISTING-IN MACHINE COMPANY, OF BROOKLYN, NEW YORK, A CORPORATION OF NEW YORK.

THREAD FEEDER FOR WARP-TWISTING-IN MACHINES.

Application filed January 24, 1928. Serial No. 249,037.

This invention relates to machines, known as warp twisting-in machines, for uniting by twisting the threads of a new warp to those of the old warp, and particularly to warp twisting-in machines in which the warps are extended toward each other and are held with their end portions upstanding, and two of them at a time (one from each warp) are advanced laterally of themselves to the twisting means by mechanism including a spiral feeding device rotating on a horizontal axis. The object is to provide a spiral feeding device which shall be simple in construction, not obscure or confuse the vision of the attendant and be self-sufficient in not only efficiently feeding the threads to the twisting mechanism but in performing certain operations thereon incident to such feeding.

In the drawings,

Fig. 1 is a side elevation of a warp twisting-in machine embodying the improved spiral feeding device;

Fig. 2 is a front elevation of the spiral feeding device, with parts of the machine in section; and

Fig. 3 is a fragmentary side elevation showing the parts in another position.

The following parts of the machine are or may be substantially as heretofore (see United States Patents Nos. 648,738 and 1,403,067): The machine frame 1 having the fixed horizontal bars 2 over which the two warps A and B extend toward each other; the vertically reciprocating structure 3 sliding in frame 1 and having a clamp 4 for the upwardly extending end portions A' and B' of the two warps and a pair of forwardly projecting rods 5 which overlie the warps (Fig. 2); the horizontal guides 6 formed as a fork sliding longitudinally of itself back and forth between the rods 5 and under which guides the warps extend before their end portions extend up to the clamp 4, the same having upwardly inclined terminals 6^a formed with hooks 6^b; the twisting mechanism comprising the fixed pad 7 and the rotating pad 8 between which two threads (one from each warp), having been separated from their warps, are twisted together and during such intertwisting have their portions A' and B' cut off by the oscillated knife 9; the pairs of reciprocating hook-bars 10 and 11 which maintain leases or crosses in the warp end portions A' and B'

(Fig. 2) and in each pair have their hooks 55 oppositely projecting, said hook-bars being turned half-revolutions and on each such movement drawing the main body of each portion A' B' back, so that the outermost thread of each stands clear; the oscillating 60 finger 12 which separates these two threads from the main bodies A' and B' so that the spiral (to be described) can intervene and then feed such two threads to the twisting mechanism; and the mechanism in part 65 shown at the right of the frame in Fig. 1, for causing the necessary cooperative functioning of those of the foregoing parts which have movement, to wit: the reciprocation of structure 3, with its clamp 4 70 and rods 5, the rotation of member 8 of the twisting mechanism and oscillation of knife 9, the reciprocation of fork 6, the reciprocation and rotating of the hook-bars, the oscillation of finger 12, and the rotation 75 of said spiral feeding device. The vertical movement of structure 4—3—5 is not material to the present invention, being designed as usual principally to agitate the warps, each maintained with a lease or cross by the 80 hook-bars, and break down filamentous linking together of their constituent threads.

Said device in the example illustrated includes a hub or body portion 13 fixed on a rotating shaft 14 and the spiral portion 15 85 progressing spirally around the axis of the hub and which springs from one end of the hub and has its other end free and projecting inwardly toward frame 1 so as to enter between the main warp bodies and the two 90 threads separated therefrom by finger 12 to start the feeding of the latter on each revolution.

1: There will be always several pairs of threads undergoing advancement besides the pair undergoing twisting, as at portions I, II and III, Fig. 1. The pair at III is next to slide up the inclined terminals 6^a of the guides or arms 6 of the fork (then almost at its outward limit) toward the twisting 100 mechanism, structure 4—3—5 having risen, as shown, to permit this. The pair at III should be urged forward, so as to be positioned for sliding up the inclines of 6^a, in a positive and quick manner thus to insure 105 parting this pair from one or both of the pair at II and leaving the latter behind should they be caught therewith in any way. Hence

spiral 15 according to this invention, not only has as to its volute portion which extends from *b* rearward, say to *a* in Fig. 1, a greater pitch than the next inward volute portion 5 but at point *c* it is formed to pass closer to guides 6 than the latter portion, that is, with a radially outward bulge (Fig. 2). Consequently not only does the pair at II tend to lag behind the pair at III up to the instant 10 when the latter should be transferred to the inclines 6^a but at that instant the pair at III receive a positive and quick forward impulse effective to separate them from either or both of the pair at II should the latter be caught 15 therewith.

2. When the thread slides up inclines 6^a and becomes caught by hooks 6^b of guides 6, the latter, advancing, bring them where they should stand stretched between such hooks 20 and an abutment formed by the crotch of a fixed fork 16, with their stretched portions in the twisting plane—coincident with the acting faces of pads 7—8, otherwise there will be a failure to twist. According to this invention the spiral portion 15 of itself performs this function, in the example shown by being made to spring from the outer side of body portion or hub 13, as at *x*, and then to cross its periphery in spaced relation thereto, 25 as at *y*, Figs. 1 and 3. When the part *x*—*y* acts on the thread pair at IV it bends them around the hub periphery (see Fig. 3, showing the position to which the spiral device has now rotated), whose inner side is slightly 30 outward of said plane and opposes the advance of the threads, so that they become fully seated at the abutment.

Thus, without auxiliaries, a simple form of spiral device is effective to perform the 40 general function of feeding the pairs of threads successively and in particular (1) insures the threads III rising up the inclines without taking another thread or threads with them and (2) causes each pair of threads 45 to become stretched exactly in the plane for twisting.

Having thus fully described my invention, what I claim is:

1. In a warp twisting-in machine, the combination of a frame, a pair of horizontal guides projecting from the frame and between which the two warps extend and having upwardly inclined terminals, means above the guides to hold the two ends of the warp, 50 and a rotating spiral device, journaled with its axis horizontal and relatively between said means and guide, for advancing the threads along the guides to the terminals successively in pairs each comprising a thread from each 55 warp, the spiral of said device having that volute portion thereof which advances the threads along the parts of the guides imme-

dately adjoining their terminals of greater pitch than that volute portion thereof which advances the threads to said parts and having the first-named portion thereof formed to pass closer to the guides than its second-named portion. 65

2. In a warp twisting-in machine, the combination of a frame, a pair of horizontal guides projecting from the frame and between which the two warps extend and having upwardly inclined terminals, means above the guides to hold the two ends of the warp, 70 and a rotating spiral device, journaled with its axis horizontal and relatively between said means and guide, for advancing the threads along the guides to the terminals successively in pairs each comprising a thread from each 75 warp, the spiral of said device having that volute portion thereof which advances the threads along the parts of the guides immediately adjoining their terminals of greater pitch than that volute portion thereof which advances the threads to said parts and having the first-named portion thereof formed to pass closer to the guides than that volute portion thereof which advances the threads to said parts. 80

3. In a warp twisting-in machine, the combination of spaced means to hold the warp threads taut, an abutment spaced from one such means and against which the threads are to be advanced to thereupon lie stretched between the abutment and latter means, and rotary thread advancing means having its axis extending lengthwise of the path of advance of the threads and including a body portion and an elongated portion having one end connected to the body portion, progressing spirally around said axis opposite to the direction of advance of the threads and having its other end free, said elongated portion having between its ends a surface formed to cam the threads against said abutment. 90

4. In a warp twisting-in machine, the combination of spaced means to hold the warp threads taut, an abutment spaced from one such means and against which the threads are to be advanced to thereupon lie stretched between the abutment and latter means in a given plane, and rotary thread-advancing means comprising a hub having its axis lengthwise of the advance of the threads and one side thereof arranged to oppose such advance of the threads but relatively beyond said plane in the direction of such advance and a thread-feeding spiral progressing around said axis and having a free end directed relatively opposite to the direction of advance of the threads, said spiral springing from the other side of the hub and crossing the periphery thereof in spaced relation to 100 such periphery. 105

In testimony whereof I affix my signature.

JOHN H. BECKER.
